(57) **CLAIM**

The ornamental design for a collapsible pencil cup, as shown and described.

DESCRIPTION

FIG. 1 is a perspective view of a collapsible pencil cup in an assembled state showing our new design;

FIG. 2 is a front elevation view of the collapsible pencil cup;

FIG. 3 is a left side elevation view of the collapsible pencil cup, the right side elevation view being a mirror image of the left side elevation view;

FIG. 4 is a top plan view of the collapsible pencil cup;

FIG. 5 is a rear elevation view of the collapsible pencil cup; FIG. 6 is a bottom plan view of the collapsible pencil cup; and,

FIG. 7 is an inverted top plan view of the collapsible pencil cup in a collapsed state.
